UNITED STATES PATENT OFFICE

ARTHUR VON FRANKENBERG, OF NEW YORK, N. Y.

DESIGN FOR AN ASH TRAY OR SIMILAR ARTICLE

Application filed November 14, 1930. Serial No. 37,648. Term of patent 7 years.

To all whom it may concern:

Be it known that ARTHUR VON FRANKENBERG, citizen of the United States, and resident of New York city, in the county of New York and State of New York, has invented a new, original, and ornamental Design for an Ash Tray or Similiar Article, of which the following is a specification, reference being had to the accompanying drawing, forming part thereof, in which the figure is a perspective view of an ash tray embodying my new design.

I claim:

The ornamental design for an ash tray or similar article, substantially as shown.

Dated, November 11, 1930.

ARTHUR VON FRANKENBERG.
